UNITED STATES PATENT OFFICE.

WALTER LARKIN, OF NORRISTOWN, PENNSYLVANIA, ASSIGNOR TO FIDELITY MACHINE COMPANY, OF PHILADELPHIA, PENNSYLVANIA, A CORPORATION OF DELAWARE.

DOGLESS KNITTING MACHINE.

Application filed May 15, 1925. Serial No. 30,559.

One object of this invention is to provide a relatively simple, substantial device for removably supporting the dial post and dial of a rib knitting machine in such manner as to permit of the feeding thereto of one or more threads, the arrangement being such as to permit of the convenient vertical adjustment of the dial and the provision of a relatively long vertical support for the dial post.

A further object of the invention is to provide a dogless attachment whose construction shall be such as to avoid the necessity for movable pawls or dogs customarily employed to prevent rotation of the dial post while permitting the free delivery to the needles of the thread required for knitting.

These objects and other advantageous ends I attain as hereinafter set forth, reference being had to the accompanying drawings, in which:

Figure 1 is a vertical section illustrating the detail construction of a dogless attachment constructed in accordance with my invention, and

Fig. 2 is a horizontal section on the line 2—2, Fig. 1.

In the above drawings, 1 represents a portion of the fixed structure of a rib knitting machine including upwardly projecting posts 2 on which are rigidly mounted the supporting arms 4 of a circularly curved base piece 3. The knitting machine includes a relatively stationary needle cylinder 5 and a rotary cam ring 6 carried upon a rotary structure 7 from opposite sides of which two posts 8 project upwardly and are engaged at their upper ends with the arms 9 of a ring 10.

Mounted to cooperate with the cylinder is a dial 11 carried adjacent the lower end of a dial post 12 which serves to rotatably support the dial cam ring 13. The latter is rotated synchronously with the cylinder cam ring 6 by suitable connections, (not shown).

In accordance with my invention I mount on the top of the ring 10 and rigidly fix to the same, by means such as the screw 14, a bevel gear 15 and provide this with a relatively long hub 16 extending down and laterally bracing the dial post 12 to within a relatively short distance of the top of the

dial cam ring 13. This gear has a vertically extending passage 17 for the thread or yarn to be delivered to the needles of the machine and its periphery has a bearing in an annular portion 18 of a member 19 mounted on and rigidly fastened to the base piece 3.

This member also provides a bearing for the hub 20 of a second bevel gear 21 rotatable on an axis at right angles to the center line of the gear 15 with which its teeth engage. A passage 22 extends through this hub 20 and through the gear 21 in a line inclined to its axis of rotation, said passage preferably opening at the center of the outer face of said hub and to one side of the center of the opposite face of the gear.

The dial post 12 has its upper end bent or formed at an angle of 45° to its main portion and its extremity is given a vertically extended parallel-sided form as indicated at 23. In the case shown, said extremity is substantially rectangular in section and it slidably fits into a slot in the head 24 of a bearing member 25, rotatably mounted in and concentric with the hub 20 of the gear 21.

Set in the top face of the gear 15 around the guide post 12 is a hardened bearing ring 26, and the post 12 is provided with a vertical tapped passage for a set screw 27 which projects on the under side of the inclined portion of the post 12 and engages the upper surface of the said ring 26. It will be apparent that the set screw 27 provides means for vertically adjusting the post 12 in its bearing, and a second set screw 28 enters the side of the post 12 and is adapted to bear against the set screw 27 whereby the latter is positively secured in its adjusted position.

An open centered guard plate 29 is suitably secured to the base piece 3 and provides a shield for the toothed portions of the bevel gears 15 and 21, as clearly illustrated.

With the above described arrangement of parts, power is applied to rotate the cam ring 6 in any of the customary ways, and with it the rotary structure 7 including the post 8 and the gear 15. The yarn *x* is fed to the needles of the cylinder 5 and dial 11 through the passage 22 in the gear 21 and the passage 17 in the gear 15.

It will be noted by reference to Fig. 1 that when the inner end of the passage 22 is

in the elevated position overlying the top of the post 12, the passage 17 is at that side of the gear 15 farthest away from the gear 21. With this arrangement, as the passage 5 17 passes under the post 12, the inner end of the passage 22 also passes under, and the thread is thereby passed freely around the post.

When the dial post with its associated 10 parts is to be removed, this may be accomplished with utmost convenience by merely releasing the member 19 from the base piece 3 and releasing the nuts 30 which secure the ring 10 to the post 8. The post with its 15 associated parts may then be lifted from the machine and the separate parts removed as may be desired.

The device is an extremely simple one 20 providing for convenient vertical adjustment of the dial with the set screw 27, and providing also for an extended bearing for the post 12, as previously described, giving great strength and durability.

The simple arrangement of gears and 25 passages also provides for the entire elimination of movable pawls or dogs heretofore employed to prevent rotation of the dial post while permitting free delivery thereto of the thread required for knitting.

30 I claim:

1. The combination in a rib knitting machine, of a cylinder, a dial, and means for holding the dial from turning relatively to the cylinder including a pair of coacting rotary members having relatively fixed axes with the axis of one of said members coinciding with the axis of the dial, and a yarn passage in each of said coacting rotary members for co-operatively carrying a thread 35 around the dial holding means.

2. The combination in a rib knitting machine, of a cylinder, a dial, a rotary structure in which said dial is suspended, means for preventing rotation of the dial including a relatively fixed rotary member coactive with the rotary structure from which the dial is suspended, and co-operative yarn 45 guides in said rotary member and in the said rotary structure, for carrying a knitting thread around the suspending means and the rotation preventing means of the dial.

3. The combination in a rib knitting machine, of a cylinder, a rotary yarn guide, a 55 second rotary yarn guide, the axes of rotation of said guides being at an angle to each other, a dial and means for holding the dial from turning relatively to the cylinder including a member co-axially mounted in and relatively movable about said axis with respect to said second yarn guide, said yarn guides co-operating to carry a knitting thread around said axes and the dial holding means.

60 4. The combination in a rib knitting ma-

chine, of a cylinder, a dial, a dial post, a yarn guide member rotatable about said post, a second yarn guide member rotatable at an angle to the first mentioned guide, a member journalled in said second guide and engaging 70 the outer end of said dial post, and yarn passages formed in said yarn guide members for co-operatively carrying a knitting thread around the dial post and its engaging member.

5. The combination in a rib knitting machine, of a cylinder, a dial, a dial post, a yarn guide member rotatable about said post and having an eccentrically arranged yarn passage therein, means for supporting the post of said member, a second yarn guide member rotatable at an angle to the first-mentioned guide and having an eccentrically arranged yarn passage therein, a member journalled in said second guide and 75 engaging the outer end of said dial post for preventing rotation of the said post, and means for synchronously rotating said guide members whereby a thread passing through the passage therein is carried around the 80 said post and its engaging member.

6. The combination in a rib knitting machine of a cylinder, a dial, means including a relatively rotary structure and a dial post for supporting the dial, rotary cam mechanism for the cylinder and dial, a rotary member supported by the frame and having a yarn passage therein for guiding the yarn to the needles, with a second yarn guide member rotatable at an angle to the first 100 and having a yarn passage formed therein, means carried by said second yarn guide for preventing rotation of the dial post, and means for synchronizing the motion of the yarn guide members to carry a thread 105 around the said dial post and the means which prevent its rotation.

7. The combination in a rib knitting machine, of a frame, a cylinder, a dial, means including a relatively rotary structure for 110 supporting the dial, rotary cam mechanism for the cylinder and dial, a rotary member supported by the frame, with a dial post maintained in a relatively fixed position by said member and preventing the dial from 115 rotating, yarn passages in said rotary structure and said rotary member for guiding the yarn to the needles, around the dial post and under the portion thereof which said rotary member engages.

8. The combination in a rib knitting machine, of a cylinder, a dial, a rotary structure for supporting the dial, a yarn guide member carried by the structure coaxial with the dial, a dial post supported in said member, a second yarn guide member rotatable at an angle to the first-mentioned yarn guide, means carried by the said second yarn guide and engaging the said post to prevent rotation thereof with respect to said supporting 125 130

structure, and yarn passages formed in said yarn guide members for carrying a knitting thread around and under the dial post engaging means.

9. The combination in a rib knitting machine, of a frame, a cylinder, a dial, a dial post, means including a rotary structure for supporting the dial, rotary cam mechanism for the cylinder and dial, a rotary yarn guide member carried by the said rotary structure, a second rotary yarn guide member carried by the frame, means carried by said second guide member and engaging the said dial post for preventing rotation of the dial, and yarn passages formed in said yarn guide members for carrying a knitting thread around said dial post and under the means which prevent rotation of the dial.

10. The combination in a rib knitting machine, of a frame, a cylinder, a dial, a dial post, means including a relatively rotary structure for supporting the dial and having an eccentrically arranged yarn passage formed therein, a rotary yarn guide member carried by the frame and having an eccentrically arranged yarn passage formed therein, a member carried by the said yarn guide member adapted to engage the said dial post to prevent rotation of the dial, and means for synchronizing the motions of said rotary elements whereby a thread passing through said yarn passages is carried around the dial post and the engaging member therefor when the elements are rotated.

11. The combination in a rib knitting machine, of a frame, a cylinder, a dial, a dial post, means including a rotary structure for supporting the dial concentric with said dial post and having an eccentric yarn passage formed therein, rotary cam mechanism for the cylinder and dial, a rotary yarn guide member supported by the frame and having an eccentric yarn passage formed therein, a member journaled concentrically in the yarn guide and adapted to engage the said dial post to prevent rotation of the dial, and means for synchronizing the motions of said rotary elements whereby a thread passing through said yarn passages is carried around said dial post and the engaging member therefor when the elements are rotated.

12. The combination in a rib knitting machine, of a frame, a cylinder, a dial, a dial post, means including a rotary structure for supporting the dial, a yarn guide member in the form of a bevel gear carried by the said rotary structure concentrically with the dial post, an eccentrically positioned yarn passage in said bevel gear, a second yarn guide member in the form of a gear journaled in the said frame and meshing with the said first gear, an eccentrically positioned yarn passage in said second gear, and a member journaled in said gear and adapted to engage the dial post to prevent rotation of the dial, said yarn passages being so arranged relative to each other that the thread passing therethrough is carried around the dial post and the said engaging member therefor when said gears are rotated.

13. The combination in a rib knitting machine, of a frame, a cylinder, a dial, a dial post, means including a rotary structure for supporting the dial, a yarn passage in said rotary structure, means for adjusting the post vertically in the structure, a rotary yarn guide member having a yarn passage therein and journaled in the frame, a member journaled in the yarn guide member and having a vertical slot engaged by the end of said dial post, and means for synchronizing the rotary motion of said rotary members whereby the yarn passages therein are contiguous when passing under the dial post.

14. The combination in a rib knitting machine, of a frame, a cylinder, a dial, means including a post and a rotary structure for supporting the dial, a bevel gear carried by said structure coaxial with the dial post, a yarn passage in said gear, a second bevel gear meshing with the first and journaled in the frame, and a member journaled in said second gear and engaging the dial post to prevent rotation of the said post, said second gear having a yarn guide passage eccentric at least in part to said post-engaging member and so arranged with respect to the yarn guide passage in said first gear that the two are contiguous when passing under the dial post.

WALTER LARKIN.
